HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 7, 1925. Serial No. 60,959.

My invention relates to railway traffic controlling apparatus, and particularly to apparatus of the type comprising train carried governing mechanism controlled by code impulse combinations received from the trackway.

In apparatus of this type it has been suggested to supply the trackway with different code impulse combinations, and to provide trains with governing mechanism selectively responsive to such codes. One feature of my present invention is the provision, in apparatus of such character, of train carried governing mechanism comprising slow acting relays for differentiating between the various codes.

I will describe several forms of apparatus embodying my invention, and will then point out the novel features thereof in claims.

In the accompanying drawings, Fig. 1 is a diagrammatic view showing one form of trackway apparatus embodying my invention. Fig. 2 is a diagrammatic view showing one form of train carried governing mechanism suitable for cooperation with the trackway apparatus illustrated in Fig. 1 and also embodying my invention. Figs. 3, 4, 5 and 6 are views showing modified forms of the apparatus illustrated in Fig. 2 and also embodying my invention.

Similar reference characters refer to similar parts in each of the several views.

Referring first to Fig. 1, the reference characters 1 and 1^a designate the track rails of a stretch of railway track over which traffic normally moves in the direction indicated by the arrow. These track rails are divided, by means of insulated joints 2, into a plurality of successive track sections A—B, B—C, etc. Each such track section is provided with a track relay designated by the reference character R with an appropriate distinguishing exponent and connected across the rails adjacent the entrance end of the associated section. Each track section is also provided with a track transformer designated by the reference character T with an exponent corresponding to the location and having a secondary 4 connected across the rails adjacent the exit end of the corresponding section. Associated with each track relay R is a second relay designated by the reference character Q with an exponent corresponding to the location and which

relay, for purposes of explanation, I shall term a "transmitting" relay.

Current is supplied to the various parts of the apparatus from a series of line transformers each designated by the reference character S with an appropriate distinguishing exponent and one of which is located adjacent the junction of each two track sections. The primary 7 of each such line transformer S is constantly supplied with alternating current from some suitable source such as an alternator M over line wires 3 and 3^a.

Referring particularly to relay Q^B, this relay is provided with a circuit which passes from secondary 6 of transformer S^A, through wires 8 and 9, back contact 10 of track relay R^A, wire 11, back contact 12 of relay Q^B, wire 13, winding of relay Q^B and wires 14, 15, 16 and 17 back to secondary 6 of transformer S^A. It will be seen that this circuit is closed only when relay R^A is de-energized and relay Q^B is also de-energized. Assuming that relay R^A is de-energized, current is supplied over the circuit just traced to the winding of relay Q^B. This relay thereupon becomes energized. The opening of back contact 12 of relay Q^B opens its own circuit and the relay therefore becomes de-energized again. As long as back contact 10 of relay R^A is closed relay Q^B is intermittently energized and operates to open and close its contacts at a uniform rate. The control of each of the remaining relays Q is similar to that just described for relay Q^B. Relays Q are adjusted so that the times required for complete cycles of these relays are the same for all the relays.

Each relay Q controls the supply of current to the section in the rear in accordance with traffic conditions in advance. Referring particularly to section A—B, transformer T^B for this section is provided with two circuits. One of these circuits passes from secondary 6 of line transformer S^B, through wire 17, front point of contact 18 of relay R^B, wire 19, back contact 20 of relay Q^B, wires 21 and 22, primary 5 of transformer T^B and wires 23, 15 and 24 back to secondary 6 of transformer S^B. This circuit is closed only when relay R^B is energized and relay Q^B is deenergized. If, therefore, relay R^B is energized and relay Q^B is continuously de-energized, the circuit just

- traced for transformer T^B is continuously closed, and an uninterrupted alternating current is supplied to the rails of section A—B, wherefore track relay R^A is energized.
- 5 If, however, section A—B is occupied by a train so that relay R^A is de-energized, the closing of back contact 10 on this relay completes the operating circuit for relay Q^B , which commences to oscillate. Still assuming track relay R^B to be energized, the circuit just traced for transformer T^B is closed only for a brief interval once during each cycle of relay Q^B and the rails of section A—B are then supplied with current in the 10 form of impulses of energy separated by time intervals. The current then supplied to the trackway I shall term the "proceed" code. Another circuit for transformer T^B may be traced from secondary 6 of transformer S^B , though wire 17, back point of contact 18 of relay R^B , wire 25, a front point and a back point of contact 26 of relay Q^B in parallel, wire 22, primary 5 of transformer T^B and wires 23, 15 and 24 back to 15 20 secondary 6 of transformer S^B . If relay R^B is de-energized and relay R^A is energized alternating current is continuously supplied to section A—B over back point of contact 26 of relay Q^B . If however relay R^A is de-energized when relay R^B is de-energized the 25 30 intermittent operation of relay Q^B closes the circuit for primary 5 of transformer T^B for a brief interval at each extremity of the stroke of relay Q^B . Section A—B is then supplied according to what I shall term the "caution" code, with impulses of energy uniformly spaced apart and transmitted to the trackway at the rate of two impulses for each complete cycle of relay Q^B .
- 35 40 The operation of the apparatus associated with the remaining sections is similar to that just described in connection with section A—B.

As shown in the drawing the section to the right of point C is occupied by a train indicated diagrammatically at V^A . Relay R^C is therefore de-energized but relay R^B is held in its energized condition by alternating current continuously supplied to the 45 50 rails of section B—C by transformer T^C , and the circuit for relay Q^C is therefore interrupted at back contact 10 of relay R^B . Similarly, section A—B is continuously supplied with alternating current over back contact 20 of relay Q^B , which relay is continuously de-energized because its circuit is open at back contact 10 of relay R^A , now energized.

I will now assume that a train V moves 60 65 through the stretch of track shown in the drawing. As this train enters section A—B the de-energization of relay R^A completes the operating circuit for transmitting relay Q^B , which relay commences to oscillate. Relay R^B is energized and the proceed code is

therefore supplied to section A—B. As the train enters section B—C the de-energization of relay R^B completes the operating circuit for transmitting relay Q^C . Relay R^C is de-energized however, and current is therefore supplied to the rails of section B—C according to the caution code. It should be pointed out that the alternating current supplied to the track rails of any section is broken up into code impulse combinations only when that section is occupied by a train. While the train is occupying both sections A—B and B—C, relay R^B being de-energized, current is supplied to section A—B according to the caution code. When the train moves out of section A—B, relay R^A is no longer shunted and the first impulse transmitted to the trackway causes relay R^A to become energized. The opening of back contact 10 of relay R^A interrupts the circuit for relay Q^B and the latter relay is then continuously de-energized. Current is therefore supplied continuously to section A—B by transformer T^B over back point of contact 18 of relay R^B and relay R^A remains energized. When the train passes out of section B—C relay R^B becomes energized so that current is then supplied to transformer T^B over front point of contact 18 of relay R^B , but this does not affect any of the other apparatus associated with section A—B and relay R^A continues to be energized.

Referring now also to Fig. 2 the train carried governing mechanism comprises two magnetizable cores 27 and 27^a located in advance of the forward axle 29 and disposed in inductive relation to the two track rails respectively. Core 27 is provided with a winding 28 and core 27^a is provided with a similar winding 28^a, the two windings 28 and 28^a being connected in series so that the voltages induced therein by alternating currents flowing in opposite directions in the two track rails at any instant are additive. These two windings are connected, preferably through an amplifier 30 and a rectifier 31, with a train carried relay designated by the reference character D, and which for purposes of explanation I will call the main relay. When the rails of the stretch of track occupied by the train are being supplied with code impulse combinations, relay D will be energized during each energy impulse and will be de-energized during the time interval between such impulses. Associated with main relay D are two slow releasing relays E and F. Each time relay D becomes energized an impulse of energy is supplied to relay E over a circuit which may be traced from a suitable source of energy such as a battery 34 through wires 35, 36, 37 and 38, front contact 39 of relay D, wire 40, winding of relay E and wires 41, 42, 43 and 44 back to battery 34. When relay E is energized a circuit is completed for relay F,

which circuit passes from battery 34, through wires 35, 36, 37 and 45, front contact 46 of relay E, wire 47, winding of relay F and wires 48, 42, 43 and 44, back to battery 34. It will be clear therefore that each time relay D becomes energized, relays E and F both become energized. When the main relay next becomes de-energized the opening of back contact 39 thereon interrupts the 10 circuit for relay E. Due to the slow releasing characteristic of relay E a time interval elapses between the de-energization of relay E and the opening of its front contact 46. At the expiration of this time interval the 15 circuit for relay F becomes opened and that relay, after a similar time interval, reverses its contacts. The relays E and F therefore operate in cascade to measure the time interval elapsing between successive energizations 20 of relay D.

Relay D also comprises an armature 32 which is arranged to close a transit contact 33 for a brief interval each time the armature 32 moves from the position corresponding 25 to the de-energized condition of relay D to the position corresponding to the energized condition of this relay.

The transit contact 33, in conjunction with 30 relays E and F, controls two bridging relays J and K which, in turn, control governing means here shown as indicator lamps 59, 60 and 61. The circuit for relay J passes from battery 34, through wires 35 and 36, transit contact 33 of relay D, wire 49, front contact 35 50—50^a of slow releasing relay F, wire 51, back contact 52 of slow releasing relay E, wire 53, winding of bridging relay J, and wires 54, 55, 43 and 44 back to battery 34. It will therefore be plain that if relay E is open 40 and relay F is closed, relay J will receive a surge of energy each time transit contact 33 is closed. The circuit for relay K passes from battery 34, through wires 35 and 36, transit contact 33 of relay D, wire 49, back contact 45 50—50^b of relay F, wire 56, winding of relay K and wires 55, 43 and 44 back to battery 34. If, therefore, relay F is open, relay K will receive a surge of energy each time the transit contact 33 of relay D is closed.

50 In explaining the operation of the apparatus as a whole, I will first assume that the train occupies a stretch of track which is being supplied with a proceed code, as for example, section A—B of Fig. 1.

55 Relay D is therefore energized once for each complete cycle of the transmitting relay Q^b. Each time relay D becomes energized, the closing of front contact 39 picks up relay E, which in turn picks up relay F. When relay D next becomes de-energized the opening of contact 39 interrupts the circuit for relay E but relay F is then held in its energized condition over front contact 46 of relay E. After the expiration of the time interval 60 required for the release of relay E, contact 46 opens and contact 52 of this relay closes. At the expiration of another time interval relay F releases. The parts are so proportioned that when the proceed code is being received the time between successive energizations of relay D is long enough for both relays E and F to release. During each energization of relay D the transit contact 33 is closed for a brief interval, and since we have seen that during the time interval between successive impulses supplied to relay D relays E and F both become released, it will be plain that relay F is open each time the transit contact 33 is closed, so that relay K receives an impulse of energy over back contact 50—50^b of relay F and contact 33 for each impulse of the proceed code. Relay K is sufficiently slow releasing to bridge the time interval between successive energizations and the relay therefore maintains its front contact closed. It should be pointed out that because front contact 50—50^a of relay F is open when transit contact 33 is closed, relay J is not supplied with energy when the train is receiving a proceed code and therefore this relay is open. Current therefore flows from battery 34, through wires 35 and 57, back contact 58—58^b of relay J, proceed lamp 59, front contact 62—62^a of relay K, and wires 63 and 44 back to battery 34. Lamp 59 therefore is lighted and so indicates proceed.

I will next assume that the stretch of track occupied by the train V is being supplied with the caution code. Under this condition relay D is energized twice for each complete cycle of the transmitting relay Q. During each energization of relay D, relays E and F both become energized as explained in connection with the proceed code, but the interval of time between successive energizations of relay D is now shorter than before. The parts are so proportioned that during each time interval relay E becomes released but relay F does not have time to release. Each time relay D becomes energized, therefore, the closing of transit contact 33 supplies a surge of energy to relay J over front contact 50—50^a of slow releasing relay F and back contact 52 of slow releasing relay E. Relay J is made sufficiently slow releasing to bridge the time interval between successive surges of energy thus supplied to it and so the relay maintains its front contact closed. Relay K, under these conditions, is de-energized, its circuit being open at back contact 50—50^b of slow releasing relay F, and therefore a circuit is completed from battery 34, through wires 35 and 57, front contact 58—58^a of relay J, caution lamp 60, back contact 62—62^b of relay K, and wires 63 and 44 back to battery 34. Lamp 60 therefore becomes lighted to indicate caution.

It should be pointed out that should relay

D become continuously energized or continuously de-energized, transit contact 33 would remain open and relays J and K would both be de-energized. Under these 6 conditions current would flow from battery 34, through wires 35 and 57, back contact 58—58^b of relay J, lamp 61, back contact 62—62^b of relay K, and wires 63 and 44, back to battery 34. Lamp 61 would then be 10 lighted to indicate stop. As shown in the drawing the parts are all in the positions corresponding to continuous energization of relay D.

Particular attention should be directed to 15 the fact that with the apparatus illustrated in Fig. 2, the relays E and F, operating in cascade, are responsive to the time interval between the end of each impulse and an intermediate point in the following impulse. 20 Since the relays E and F control the indicator lamps 59, 60 and 61 in accordance with the length of this interval it may be said that the length of each such interval is measured by the relays.

25 In the modification of the train carried governing mechanism which is illustrated in Fig. 3 the main relay D is controlled in the same manner as explained in connection with Fig. 2. Associated with this relay is an 30 auxiliary relay G. I will first assume that relay D is receiving the proceed code. The first energization of relay D completes a circuit for relay E from battery 34, through wires 35, 36 and 38, front contact 39 of relay D, wires 64 and 65, back contact 66 of relay G, wires 67 and 40, slow releasing relay E and wires 41, 68, 42, 43 and 44 back to battery 34. Energy supplied over this 35 circuit energizes relay E, but as soon as the front contacts of relay E close current flows from battery 34, through wires 35, 36 and 38, front contact 39 of relay D, wires 64 and 69, winding of relay G, wire 70, front contact 71 of relay E and wires 72, 68, 42, 43 and 44 40 back to battery 34. Relay G immediately opens its back contact, thereby interrupting the circuit just traced for relay E. The energization of relay E completes the circuit for relay F over front contact 46 of relay E 45 in the same manner as in Fig. 2.

50 It will be noticed that the closing of relay G de-energizes relay E and that the subsequent opening of contact 39 of relay D has no effect upon the apparatus. When relay 55 D is energized by the next impulse a circuit is closed for one of relays J or K depending upon the length of time between impulses. Assuming that relay D is receiving the proceed code, relays E and F both become de-energized during the interval between impulses. Then when contact 60 39 of relay D closes, current flows from battery 34, through wires 35, 36 and 38, front contact 39 of relay D, wires 64 and 65, back contact 66 of relay G, wires 67 and 49, back 65

contact 50—50^b of relay F, wire 56, winding of relay K, and wires 55, 43 and 44, back to battery 34. The energization of relay D also again completes the circuit for relay E, and when this relay closes its front contact 71, 70 relay G becomes energized, opening the circuit just traced for relay K. During the time this circuit is closed, however, a surge of energy is delivered to relay K, and the relay becomes energized. As long therefore, as relay D receives the proceed code, relay K receives a surge of energy for each energization of relay D, and relay K, being slow releasing, bridges the time interval between successive surges to hold its front contact 75 closed. Lamp 59 is therefore lighted to display a proceed indication.

80 Similarly, if the relay D is receiving the caution code, the time interval between successive energizations of relays E and F permits relay E to open, but not relay F, and therefore each time relay D closes its front contact a surge of energy is delivered to relay J from battery 34 over wires 35, 36 and 38, front contact 39 of relay D, wires 64 and 65, back contact 66 of relay G, wires 67 and 49, front contact 50—50^a of relay F, wire 51, back contact 52 of relay E, wire 53, winding of relay J, and wires 54, 55, 90 43 and 44 back to battery 34. Relay J maintains its front contact closed during the interval between successive surges of energy supplied thereto, and lamp 60 is therefore lighted to indicate caution. Should relay D be continuously energized, as by the presence 95 of uninterrupted alternating current in the rails occupied by the train, or should relay D be continuously deenergized, as by the absence of such current in the rails, relays J and K would both be de-energized, and lamp 61 would be lighted to indicate stop.

100 It should be pointed out that with the apparatus here shown, the relays E and F, in cascade, measure the interval between a point in each impulse and the beginning of the next impulse. This feature has the advantage of being independent of the lengths of the impulses which may vary because of the reactance of the rails, or for other 105 reasons.

110 Under some conditions it may be desirable to control the circuit of a slow releasing relay over its own back contact so that when energy is supplied to this circuit, energizing the relay, the consequent opening of the relay's back contact will interrupt the relay circuit. I have discovered that under these 120 conditions energy must be delivered to the relay after its back contact has opened to insure that the relay will be fully energized and that the relay will have its maximum period of retardation. It is, with this arrangement of circuits, desirable to supply a surge of energy to the relay after the operating circuit for the relay is opened by the 125 130

- opening of its own back contact. In Fig. 4 I control the circuit for the slow releasing relay E over its own back contact 46 and I provide a transformer H for delivering a surge of energy to the relay after its operating circuit is opened. This relay is charged with energy during the time the operating circuit for the relay is closed. When the relay circuit is opened, the energy stored in the magnetic field about the transformer H is discharged into the relay, completing the stroke of the relay, and energizing the relay to a degree which insures the proper retardation time.
- 15 The circuit for relay E passes from battery 34, wires 35 and 36, back point of contact 46 of relay E, wire 38, front contact 39 of relay D, wires 69 and 40, winding of relay E, and wires 41, 70, 71, 42, 43 and 44 back to battery 34. Another circuit may be traced from battery 34, through wires 35 and 36, back point of contact 46 of relay E, wire 38, front contact 39 of relay D, wires 69 and 72, primary 73 of transformer H, and wires 71, 42, 43 and 44 back to battery 34. It will, therefore, be seen that when relay E is de-energized and relay D is energized, current is supplied to the winding of relay E and to the primary 73 of transformer H in parallel.
- 20 In explaining the operation of the apparatus I will first assume that relay D is de-energized. Relay E is therefore de-energized. When relay D becomes energized current is supplied to primary 73 of transformer H and to the winding of relay E as already explained. Relay E therefore becomes energized and energy is stored in the magnetic field of transformer H. When 25 back contact 46 of relay E opens, the circuits for transformer H and relay E are opened but front contact 76 of relay E immediately closes, completing a circuit from secondary 74 of transformer H through wire 40, winding of relay E, wires 41 and 77, front contact 76 of relay E, and wire 75 back to secondary 74 of transformer H. The energy which has previously been stored in the magnetic field of transformer H is therefore 30 discharged into relay E, completing the energization of this relay and insuring that the relay will require its full retardation period to open its contacts. Relay F is controlled by relay E in exactly the same manner as 35 explained in connection with Fig. 2, it being noticed that no artificial means is required to complete the stroke of relay F because that relay is supplied with energy over a front contact of relay E, which is closed for 40 a comparatively long time.
- Relays J and K are selectively controlled by the relays E and F in the same general way as in Fig. 3, but apparatus is also provided for insuring that each of these relays
- is fully energized by each surge of energy 65 supplied thereto.
- Assuming that the relay D is receiving the caution code, relay E will become de-energized during each time interval between successive energizations of relay D, but relay F will not become de-energized, during such time intervals. Each time front contact 39 of relay D closes, a circuit is closed from battery 34, through wires 35 and 36, 70 back point of contact 46 of relay E, wire 38, front contact 39 of relay D, wires 69, 72 and 49, front contact 50—50^a of relay F, wire 51, back contact 52 of relay E, wires 53, 75 78 and 79, winding of relay J, and wires 54, 90 91, 55, 43 and 44 back to battery 34. The circuit just traced is provided with a branch which passes from wire 53, through back contact 80 of relay E, wire 81, primary 82 of a transformer P^J, and wires 83 and 84, back to wire 91. It will therefore be seen that 85 when relay E is de-energized, primary 82 of transformer P^J is connected in parallel with relay J.

Secondary 86 of transformer P^J is connected with relay J through an asymmetric cell N^J, that is, a cell having the characteristic of offering a higher resistance to current flowing through the cell in one direction than to current flowing in the opposite direction. The circuit including the cell N^J 95 passes from one terminal of secondary 86 of transformer P^J, through asymmetric cell N^J, wire 79, winding of relay J, and wires 54, 84 and 87 back to secondary 86 of transformer P^J. The parts are so arranged, that 100 when current is being supplied to relay J and primary 82 of transformer P^J over the circuits including front contact 39 of relay D, the asymmetric cell N^J prevents the flow of current through secondary 86 of transformer P^J which current would be of such direction as to oppose the current in relay J. Energy is therefore stored in the transformer field. When relay E becomes energized, the circuits for relay J and primary 82 are interrupted. The energy stored in the transformer P^J is then supplied to relay J the current being of such direction that the asymmetric cell offers only a slight opposition to such current. The stored energy 105 supplied to relay J from transformer P^J completes the stroke of relay J and insures the full retardation time of the relay. A transformer P^K and asymmetric cell N^K associated with relay K operate in the same manner as explained in connection with the similar parts associated with relay J.

Lamps 59, 60 and 61 are controlled by relays J and K as explained in connection with Fig. 2.

In the modification illustrated in Fig. 5 relay E is provided with two windings 89 and 90. Winding 89 is constantly connected

with secondary 74 of transformer H. The circuit for winding 90 of relay E passes from battery 34, through wires 35, 36 and 88, back point of contact 46 of relay E, wire 38, front contact 39 of relay D, wire 40, winding 90 of relay E, and wires 41, 71, 42, 43 and 44 back to battery 34. The circuit for primary 73 of transformer H may be traced from battery 34, through wires 35 and 36, back contact 91 of relay E, wire 91^a, front contact 93 of relay D, wire 69, primary 73 of transformer H, and wires 71^a, 71, 42, 43 and 44 back to battery 34. It will therefore be seen that if relay E is de-energized and relay D becomes energized current is supplied to primary 73 of transformer H and also to winding 90 of relay E. The parts are so arranged that the current supplied to winding 89 of relay E by secondary 74 of transformer H during the first surge of current to primary 73 of transformer H opposes the current in winding 90 of relay E and prevents the operation of this relay until the current values have become steady. 25 When the field of transformer H has been built up to its maximum value the current delivered to winding 89 by secondary 74 is, of course, zero and the current then supplied to winding 90 of relay E causes the relay to operate its contacts. When back contact 46 and 91 of relay E open, the supply of current to primary 73 of transformer H and to winding 90 of relay E is discontinued. The decay of the magnetic field of 30 the transformer H supplies energy to winding 89 of relay E which completes the stroke of the relay and insures the normal retardation period of this relay. Relay F is controlled by relay E in the same manner as 35 explained in connection with Fig. 2.

Relays J and K are each provided with a transformer P as in Fig. 4. The secondaries of these transformers are controlled by contacts on the associated slow releasing relays 40 instead of by asymmetric cells N. For example I will assume that relay E is de-energized and relay F is energized as when the caution code is being received, and that relay D closes its front contact 39. During the 45 time interval prior to the opening of the back contacts of relay E a surge of energy is supplied to relay J over a circuit which passes from battery 34 through wires 35, 36 and 88, back point of contact 46 of relay E, wire 38, front contact 39 of relay D, wires 40 and 78, front contact 50—50^a of relay F, wire 51, back contact 52 of relay E, wires 53 and 79, winding of relay J, and wires 54, 91, 55, 43 and 44 back to battery 34. A 50 branch is provided for this circuit from wire 53, through back contact 80—80^b of relay E, primary 82 of transformer P^J, and wires 83 and 84, back to wire 91. It will therefore be plain that during this brief time 55 interval during which current is supplied

to relay J, a surge of energy is also supplied to primary 82 of transformer P^J. When relay E becomes energized the circuit just traced for relay J is opened and the circuit through primary 82 of transformer P^J is also opened, but the closing of front contact 80—80^a of relay E completes a circuit from secondary 86 of transformer P^J, through wire 81, front contact 80—80^a of relay E, wire 79, winding of relay J, wires 54, 84 and 87 back to secondary 86 of transformer P^J. The energy stored in the magnetic field of transformer P^J is therefore discharged through the circuit just traced and completes the stroke of relay J and insures the maximum retardation period of this relay. The operation of transformer P^K associated with relay K will be readily understood from the foregoing without further explanation. 85

It will be seen that with the apparatus shown in Figs. 4 and 5, the relays E and F, operating in cascade, measure the time interval between an intermediate point in each impulse and the beginning of the next 90 impulse.

Referring now to Fig. 6, the apparatus is similar to that shown in Fig. 2 with the exception that a third slow releasing relay L, which I shall call a checking relay, is associated with relays E and F. Relay L is energized only when relay F is energized, the circuit for the checking relay passing from battery 34, through wires 35, 36, 37 and 93, front contact 94 of relay F, wire 95, winding of relay L, and wires 96, 42, 43 and 44, back to battery 34. 95

The front contact 98 of the checking relay L is connected, by means of wires 97 and 99, between the transit contact 33 and contact 50 of relay F. 100

Relays J and K are controlled by relays E and F as already described in connection with Fig. 2, but it should be noticed that neither of these relays can be energized when 105 relay L is de-energized.

With the apparatus shown in Fig. 2, should relay F stick in its energized condition, while the proceed code is being received, relay J would be energized so that lamp 60 would be lighted instead of lamp 61. 110

With the apparatus shown in Fig. 6, this can not occur, for should relay F stick in its de-energized position, the checking relay L would remain in its de-energized condition, even though relay E should become energized. Relays J and K would therefore both remain de-energized, and lamp 61 would be lighted, no matter what code were being received by relay D. 115

Furthermore, should the time interval between successive energizations of relay D be considerably longer than the time interval corresponding to the proceed code, relay L would become de-energized after each such 120 125 130

energization and before relay D would be re-energized by the succeeding impulse. Relays J and K therefore could not become energized by the closing of contact 33. It follows that a stray code current, having impulses separated by time intervals longer than the intervals of the proceed code could have no effect upon the apparatus.

For purposes of explanation I have shown 10 the checking relay L applied to the apparatus shown in Fig. 2, but it should be clearly pointed out that any of the other views could be similarly modified.

Although I have herein shown and described only a few forms of railway traffic controlling apparatus embodying my invention, it is understood that various changes and modifications may be made therein within the scope of the appended claims without 20 departing from the spirit and scope of my invention.

Having thus described my invention, what I claim is:

1. In combination, a stretch of railway track, means for supplying said stretch with energy in the form of a series of impulses each separated from the preceding impulse by a time interval, and governing means selectively responsive to the time interval between a given point in each such impulse and a different point in the following impulse.

2. In combination, a stretch of railway track, means for supplying said stretch with energy in the form of a series of impulses each separated from the preceding impulse by a time interval, and governing means selectively responsive to the time interval between an intermediate point in each said impulse and the beginning of the following impulse.

3. In combination, a source of code impulse combinations each comprising an energy impulse and a time interval of no energy, a relay receiving energy from said source and arranged to be energized by said impulses but to be de-energized during said time intervals, and slow releasing relays for measuring the time from a point in each said impulse to a different point in the next said impulse.

4. In combination, a source of code impulse combinations each comprising an energy impulse and a time interval of no energy, a plurality of slow releasing relays, means for energizing all said relays during each said impulse, but for successively de-energizing said relays during each said time interval, and governing means controlled jointly by said slow releasing relays.

5. In combination, a main relay, means for intermittently energizing said main relay, two slow releasing relays, means for energizing both said slow releasing relays when said main relay becomes energized, 65 said slow releasing relays successively be-

coming de-energized when said main relay becomes de-energized, and governing means controlled jointly by said slow releasing relays.

6. In combination, a main relay, means for intermittently energizing said main relay, a plurality of slow releasing relays, means for energizing all said slow releasing relays when said main relay becomes energized, said slow releasing relays successively becoming de-energized when said main relay 70 becomes de-energized, and governing means controlled jointly by said slow releasing relays and by said main relay.

7. In combination, a main relay, means for intermittently energizing said main relay, a first slow releasing relay having a circuit including a contact of said main relay, a second slow releasing relay having a circuit including a front contact of said first 80 slow releasing relay, and governing means controlled jointly by said two slow releasing relays.

8. In combination, a source of code impulse combinations each comprising an energy impulse and a time interval of no current, two slow releasing relays, means for energizing both said relays during each such impulse but for successively de-energizing said relays during each said time interval, and governing means selectively responsive 90 to the length of time elapsing between successive energizations of said relays.

9. In combination, a main relay, means for intermittently energizing said main relay, slow releasing relays controlled in cascade for measuring the time intervals between successive energization of said main relay, and governing means selectively controlled by said slow releasing relays in accordance with the lengths of said time intervals.

10. In combination, a main relay, means for intermittently energizing said main relay, two bridging relays, slow acting relays controlled by said main relay for selectively operating said bridging relays in accordance with the time intervals between successive energizations of said main relay, and governing means selectively controlled by said bridging relays.

11. In combination, a first slow releasing relay, a circuit for said relay including two contacts, means for intermittently closing one of said contacts, means controlled by said first slow releasing relay for opening the remaining said contact, a second slow releasing relay controlled by said first slow releasing relay and governing means selectively controlled by said two slow releasing relays.

12. In combination, a main relay, means for intermittently energizing said main relay, a first slow releasing relay, means for supplying said first slow releasing relay with energy when said main relay becomes ener-

gized, means controlled by said first slow releasing relay for subsequently interrupting such supply independently of said main relay, a second slow releasing relay controlled in cascade by said first slow releasing relay, and governing means selectively controlled by said two slow releasing relays in accordance with the time interval between successive energizations of said first slow releasing relay.

13. In combination, a main relay, means for intermittently energizing said main relay, a slow releasing relay having a circuit controlled by its own back contact and a front contact of said main relay, means for storing energy while said circuit is closed and arranged to discharge such stored energy into said slow releasing relay immediately after said circuit is opened, means including said slow releasing relay for measuring the time interval between successive energizations of said main relay, and governing means selectively controlled by such time measuring means.

14. In combination, a main relay, means for intermittently energizing said main relay, a slow releasing relay, a circuit including a front contact of said main relay for initiating operation of said relay, means controlled by said main relay for interrupting said circuit, means independent of said circuit for completing the operation of said relay, means including said slow releasing relay for measuring the time interval between successive energizations of said main relay, and governing means selectively controlled by said time measuring means.

15. In combination, a main relay, means for intermittently energizing said main relay, a slow releasing relay, a circuit including a front contact of said main relay for initiating operation of said relay, means controlled by said main relay for interrupting said circuit, means for storing energy while said circuit is closed and arranged to discharge such stored energy into said slow releasing relay to complete the operation of said relay after said circuit is interrupted, and governing means controlled by said slow releasing relay.

16. In combination, a main relay, means for intermittently energizing said main relay, a slow releasing relay, a circuit for said slow releasing relay including its own back contact and a front contact of said main relay, a transformer having a primary connected in parallel with said relay, a secondary on said transformer, and means for connecting said secondary with said slow releasing relay immediately after said circuit is broken.

17. In combination, a main relay, means for intermittently energizing said main relay, a slow releasing relay, means for supplying energy to said slow releasing relay

when said main relay is energized, means controlled by said slow releasing relay for discontinuing said supply, and other means for storing energy during such supply and for discharging such stored energy into said slow releasing relay when said supply is interrupted, and governing means controlled by said slow releasing relay.

18. In combination, a contact arranged to be operated periodically, a relay, a source of energy, means for connecting said relay with said source during each operation of said contact, means for storing energy while said relay is connected with said source but for discharging such energy into said relay immediately after the relay is disconnected from the source, and governing means controlled by said relay.

19. In combination, a contact arranged to be operated periodically, a relay, a source of energy, means for connecting said relay with said source during each operation of said contact, a transformer having a secondary connected in parallel with said relay, an asymmetric cell connected in series with said secondary, and means for supplying energy to the primary of said transformer when energy is being supplied to said relay over said contact.

20. In combination, a relay, a transformer having a secondary connected in parallel with said relay, means for supplying direct current to said relay and to the primary of said transformer, an asymmetric cell in series with said secondary to prevent flow of current through said secondary due to the growth of the magnetic field of said transformer, but permitting the energy stored in said field to be discharged into said relay, and governing means controlled by said relay.

21. In combination, a main relay, means for intermittently energizing said main relay, a slow releasing relay, means for supplying said slow releasing relay with energy when said main relay becomes energized, means controlled by said slow releasing relay for subsequently interrupting such supply independently of said main relay, and governing means selectively controlled by said slow releasing relay in accordance with the time interval between successive energizations of said main relay.

22. In combination, a contact mechanism arranged to be intermittently operated, a relay, a circuit for said relay closed for a brief interval during each operation of said mechanism, a transformer having a primary arranged to be connected in parallel with said relay when said circuit is closed, means for connecting the secondary of said transformer with said relay immediately after said circuit is opened, and governing means controlled by said relay.

In testimony whereof I affix my signature.
HERBERT A. WALLACE.
